UNITED STATES PATENT OFFICE.

HERBERT WILSON, OF TOLEDO, OHIO, ASSIGNOR TO THE DURA COMPANY, OF TOLEDO,
OHIO, A CORPORATION OF DELAWARE.

DESIGN FOR A WINDOW REGULATOR HANDLE.

Application filed January 28, 1924. Serial No. 8,452. Term of patent 7 years.

To all whom it may concern:

Be it known that I, HERBERT WILSON, a citizen of the United States of America, residing at Toledo, in the county of Lucas and State of Ohio, have invented a new, original, and ornamental Design for a Window Regulator Handle, of which the following is a specification, reference being had therein to the accompanying drawings,

forming part thereof, in which Fig. 1 is a plan view of a window regulator handle showing my new design; Fig. 2 is a side elevation thereof; and Fig. 3 is an end elevation thereof.

I claim: The ornamental design for a window regulator handle substantially as shown.

HERBERT WILSON.
